DESIGN FOR A STOOL PEDESTAL

Kenneth E. Bemis, San Francisco, Calif.

Application May 28, 1934, Serial No. 51,945

Term of patent 14 years

To all whom it may concern:

Be it known that I, KENNETH E. BEMIS, a citizen of the United States of America, residing at San Francisco, in the county of San Francisco and State of California, have invented a new, original, and ornamental Design for a Stool Pedestal, of which the following is a specification, reference being had to the accompanying drawing, forming part thereof.

The figure is a perspective view of a stool pedestal showing my new design.

I claim:

The ornamental design for a stool pedestal, as shown.

In testimony whereof I affix my signature.

KENNETH E. BEMIS.
